UNITED STATES PATENT OFFICE

120,818

DESIGN FOR AN EMBROIDERED TRIMMING

Emil A. Pulver, Bogota, N. J.

Application January 30, 1940, Serial No. 89,888

Term of patent 3½ years

To all whom it may concern:

Be it known that I, Emil A. Pulver, a citizen of Switzerland, residing at Bogota, N. J., have invented a new, original, and ornamental Design for an Embroidered Trimming, of which the following is a specification, reference being had to the accompanying drawing, forming part thereof.

The figure is a plan view of an embroidered trimming showing my design.

I claim:

The ornamental design for an embroidered trimming, as shown.

EMIL A. PULVER.
